UNITED STATES PATENT OFFICE.

STEPHEN A. BAKALYAR, OF DES MOINES, IOWA.

PEN AND PENCIL HOLDER.

Application filed April 14, 1924. Serial No. 706,554.

To all whom it may concern:

Be it known that I, STEPHEN A. BAKALYAR, a citizen of the United States, and a resident of Des Moines, in the county of Polk and State of Iowa, have invented a certain new and useful Pen and Pencil Holder, of which the following is a specification.

The object of my invention is to provide a pen and pencil holder of simple, durable and inexpensive construction, which may be easily and quickly applied to a garment for securing the pen or pencil against becoming lost.

More specifically it is the object of my invention to provide a pencil or pen holder having improved means for positively securing the same to the wearer's pocket, and provided with means whereby it may be easily and quickly applied to or detached therefrom.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a front elevation of the upper end of the barrel of a fountain pen showing the manner in which my improved holder is applied.

Figure 2 is a side elevation of the same.

Figure 3 is a longitudinal, sectional view taken on the line 3-3 of Figure 1, showing the manner in which it is applied to a coat pocket, said pocket being in section.

Figure 4 is the same as Figure 3, with the exception that the device is shown with the locking pin released.

Figure 5 shows the same with the clamping member entirely open; and

Figure 6 shows a detail, transverse, sectional view taken on the line 6-6 of Figure 5.

My improved pencil holder comprises a body portion 10 preferably formed of a sheet of metal. The side edges of the body portion 10 are formed cylindrical so as to provide yieldable clamping members 11 designed to surround the pen barrel in the usual manner, said body portion being secured thereto by frictional engagement caused by the yieldable side members 11.

The lower end of the body portion 10 is provided with an outwardly extending flange 12 which serves as a base or support de-

signed to rest on the upper edge of the pocket member 13.

The central portion of the body portion 10 is provided with two outwardly extending ears 14 which are formed by cutting them from the members 11 and then turning them outwardly to position substantially parallel with each other and spaced apart as clearly shown in Figure 6. The said members 14 form bearings for a pivot 15. The said pivot 15 is designed to carry a pivoted clamping lever 16 which is formed substantially U-shaped in cross section, and has its lower end provided with a hollow spherical stripping member 17, said spherical portion being provided with an opening 18. The upper end 19 of the lever 16 extends upwardly and outwardly, as clearly shown in Figure 2.

Pivotedly mounted between the side members of the levers 16 is a locking lever 20 mounted on the pivot 15. The lower end of the lever 20 is provided with an inwardly extending locking pin 21. The upper end of the lever 20 is provided with an upwardly and outwardly extending handle portion 22, the lower end of which is provided with an inwardly extending pin 23 designed to pass through an opening 24 in the inner face of the member 19, said pin being designed to engage the free end of a spring member 25, which is formed from the body portion 10.

The said member 25 extends upwardly and outwardly, and thence downwardly and inwardly, as clearly shown in the sectional view. The free end of the said spring 25 is designed to engage the pin 23, while the upper end of the said spring is designed to engage the upper end of the member 19. The upper end of the spring 25, by engaging the upper end of the member 19, will cause the spherical stripping member 17 to be brought into engagement with the pocket member 13 when the pen barrel 26 is placed inside of the pocket. The free end of the spring 25 will engage the pin 23, causing the member 22 to be moved outwardly and the pin 21 to move inwardly to the opening 18 and to enter the pocket member 13.

This provides means whereby the pen holder will be rigidly and securely held against being moved from engagement with the said pocket member, the member 18 also assisting to hold the pen holder in position by friction.

When it is desired to remove the pen, the

operator simply places his finger on the member 22 and moves it inwardly, which will first cause the pin 21 to be pulled outwardly from the cloth, while the member 18 5 acts as a stripper. A further inward movement of the member 22 will cause the member 19 to engage the upper end of the spring 25, and the member 18 to be disengaged from the pocket member, as clearly shown in Figure 5. The member 12 serves as a rest or 10 guide for the pen holder while it is being placed into position, and also serves as a stop to limit the inward movement of the lower end of the lever 16 when the device is 15 not applied to a pocket.

Thus it will be seen that I have provided a pen and pencil holder of simple, durable and inexpensive construction, which may be secured to the barrel of a pen or pencil in the usual manner by the clamping devices 20 11, after which the holder may be placed in position on the user's pocket, and firmly locked in position by means of the pin 21 and the clamping member 18, and when so locked it will not accidentally come loose or lost, until the pin 21 has been withdrawn by means of the lever 22.

I claim as my invention:

1. A pencil holder comprising a body portion having clamping members for securing the body portion to a pencil, a pivoted stripper lever having a stripper on its lower end, a pivoted locking lever having a locking pin on its lower end designed to work through 30 said stripper member, and means for yieldably moving the said stripper member and said locking pin toward the pencil, for the purposes stated.

2. A pencil holder comprising a body portion having clamping members for securing the body portion to a pencil, a pivoted stripper lever having a stripper on its lower end, a pivoted locking lever having a locking pin on its lower end designed to work through 40 45 said stripper member, means for yieldably moving the said stripper member and said locking pin toward the pencil, and means for first moving the locking pin and then the stripper member outwardly from the pencil.

3. A pencil holder comprising a body por-

tion having cylindrical shaped clamping members for securing the same to a pencil, said body portion being provided with outwardly extending ears, a stripper lever pivoted between said ears, a locking lever pivoted to the same pivot member, a spherically shaped stripper member on the lower end of said stripper lever having an opening, a locking pin on the lower end of said locking 55 60 lever designed to enter the opening of said stripper member, means for yieldably moving the lower end of both of said levers toward a pencil when secured in said clamping member, means for first moving said locking pin outwardly and thence the stripper, substantially as described and for the purposes stated.

4. A pencil holder comprising a body portion having cylindrically shaped clamping members for securing the same to a pencil, the lower end of said body portion being provided with outwardly extending flange, the upper end of said body portion being provided with a spring member extending 70 75 upwardly and outwardly and thence downwardly and inwardly, said body portion also being provided with a pair of outwardly extending parallel ears, a stripper lever pivotally mounted between said ears, said lever 80 being substantially U-shaped in cross section and having its lower end provided with a hollow spherically shaped stripper member having an opening, the upper end of said lever extending upwardly and outwardly, a 85 locking lever pivotally mounted on the same pivot as the first said lever and between the side members thereof, the lower end of the locking lever being provided with a locking pin designed to enter the opening of said 90 stripper member, the upper end of said locking lever extending upwardly and outwardly and having its lower end provided with an inwardly extending pin, designed to pass through an opening in the upper end 95 of said stripper lever and to engage the free end of the spring formed from said body portion, the upper end of said spring being designed to engage the upper end of said stripper lever.

STEPHEN A. BAKALYAR.
